UNITED STATES PATENT OFFICE.

WINFIELD S. ROGERS AND WILLIS C. JONES, OF CINCINNATI, OHIO, ASSIGNEES TO P. G. MARCH, OF SAME PLACE.

RATCHET-DRILL.

SPECIFICATION forming part of Letters Patent No. 401,375, dated April 16, 1889.

Application filed September 10, 1888. Serial No. 284,974. (No model.)

To all whom it may concern:

Be it known that we, WINFIELD S. ROGERS and WILLIS C. JONES, of Cincinnati, Hamilton county, Ohio, have invented certain new and useful Improvements in Ratchet-Drills, of which the following is a specification.

This invention pertains to ratchet drills or wrenches to be operated through the medium of an oscillated hand-lever. We have illustrated our improvements in connection with a ratchet-drill designed for use as a railroad-track drill in connection with a suitable ordinary track-clamp; but our improvements are applicable, of course, to ratchet-drills designed for boiler-drilling or for general work.

Our improvements will be readily understood from the following description, taken in connection with the accompanying drawings, in which—

20 Figure 1 is a side elevation of a ratchet-drill embodying our improvements, the side here exposed to view being hereinafter designated the "left" side; Fig. 2, a partial side elevation of the opposite or right side of the 25 device; Fig. 3, an elevation of the front end of the device with the socket and ratchet-disk removed; Fig. 4, a plan of the device with portions appearing in horizontal diametrical section, and Fig. 5 a vertical transverse section of the stock and feed-screw.

In the drawings, A indicates the usual socket to receive the shank of a drill; B, a ratchet-disk formed upon or secured thereto, this disk having its teeth arranged upon a bevel-face after the manner of an ordinary bevel-gear except that the teeth are arranged in ratchet form; C, a stock or body having a socket-piece, A, journaled axially in its front end; D, the feed-screw fitted to enter an axial cavity in the rear of the stock, in which cavity the screw is capable of endwise motion but not of rotary motion, the rotary motion being prevented by any appropriate means, as by means of the spline-work illustrated, 40 the rear end of the feed-screw being fitted for engagement with the appropriate part of whatever form of clamp the implement is to be used in connection with, the illustration showing the screw as provided with a loop-bearing to engage the clamp, or the usual

clamp-frame employed in connection with railroad-track drills; E, the feed-nut threaded upon the feed-screw, and bearing against the rear end of the stock and having its periphery provided with ratchet-teeth; F, a pair of 55 oppositely-disposed trunnions carried by the stock near the ratchet-disk B, the axis of these trunnions being at right angles to the axis of rotation of the drill-socket; G, the hand-lever by which the device is operated, this hand-lever being bifurcated at its lower end, and its bifurcations journaled upon the trunnions F; H, a bevel-segment at the lower end of the left bifurcation of the hand-lever, this segment being formed after the manner of bevel-gear- 60 ing to correspond with the bevel-ratchet B, and being provided with upwardly-presenting ratchet-teeth to engage the teeth of the ratchet-disk B, the segment H and ratchet-disk B thus intermeshing like bevel-gear- 65 ing, except as to the form of the teeth, which, as before said, are ratchet form; J, a similar segment at the foot of the right-hand bifurcation of the hand-lever, the teeth of this right segment having downwardly-presenting teeth, 70 in order that they may properly engage the teeth of the disk B; K, the pivot-bearing of the left bifurcation of the hand-lever, forming the engagement with the appropriate trun- 75 nion F, this pivot-bearing, however, instead of being circular having a diagonally-disposed slot, whereby the left foot of the hand-lever and the segment H are capable of a movement diagonally to and from the face of the ratchet-disk B, thus permitting the seg- 80 ment H to be moved into and out of engage- 85 ment with the teeth of the ratchet-disk B; L, a similar slot forming the pivot-bearing of the right foot of the hand-lever; M, a shank and socket exemplifying the means for journal- 90 ing the drill-socket A in the front end of the stock, and N a pawl projecting rearwardly from the hand-lever in position to engage the teeth of the feed-nut E when the hand-lever is properly adjusted.

95 By inspecting Fig. 1 it will be seen that the left segment has its teeth in engagement with the teeth of the ratchet-disk B. If the hand-lever be oscillated rearwardly, movement of rotation will be transmitted to the ratchet- 100

disk B and to the drill-socket in the proper direction for drilling. During this movement of the hand-lever the teeth of the right segment, J, will be automatically disengaged from the teeth of the ratchet B, as indicated in Fig. 2. Upon the return-stroke of the hand-lever the teeth of the right segment, J, automatically engage the teeth of the ratchet-disk, the teeth of the left segment, H, immediately disengaging, and movement of rotation in a proper direction for drilling will again become transmitted to the ratchet-disk and drill-socket. By this means the movement of the hand-lever in each direction is caused to give rotation in a single direction to the drill-socket, and the oscillating motion of the hand-lever becomes converted into a practically continuous rotation of the drill-socket. The engagement and disengagement of the segment-teeth are accompanied by a slight twisting motion of the lever G, which motion is, however, automatic.

The rotation of the feed-nut E, in an obvious manner, causes the forward feed of the drill. When the hand-lever is depressed far enough, the pawl N engages the teeth of the feed-nut and gives that nut a partial rotation and produces the feeding movement. The rate of feed is under the control of the operator, who may depress the hand-lever so far at each of its downward movements as to produce a feeding movement, or he may carry the depression of the hand-lever to this extent on occasions only, as called for by the requirements of feed. In setting the drill to its work and in restoring the feed-screw to its short position, the nut E is free to be turned by the fingers, being normally free from engagement with the pawl N.

We claim as our invention—

40 1. In mechanism to be given movement of rotation through the medium of an oscillating lever, the combination, substantially as

set forth, of a rotatory disk having a bevel-face provided with ratchet-form teeth, a pair of trunnions or pivots arranged with their axes in the plane of and at right angles to the axis of rotation of said disk, a bifurcated lever fitted to oscillate on said pivots and engage the same by diagonally-slotted pivot-bearings, and segments at the pivot portions of said lever provided with ratchet-form teeth adapted to engage the teeth of said disk upon opposite sides of its axis.

2. In a ratchet-drill, the combination, substantially as set forth, of stock C, provided with trunnions F, drill-socket A, journaled axially in the front end thereof, bevel-disk B upon the drill-socket and provided upon its bevel-face with ratchet-form teeth, bifurcated hand-lever G, engaging said trunnions by slot-bearings K and L, and segments H and J upon said hand-lever and provided with ratchet-form teeth adapted to engage the teeth of disk B.

3. In a ratchet-drill, the combination, substantially as set forth, of a stock, a drill-socket journaled axially therein, a hand-lever connected with said stock by a pivot of oscillation having its axis at right angles to the axis of said stock, means for transmitting motion from said hand-lever to said drill-socket, a pawl projecting from said hand-lever in the direction of its motion of oscillation, and feed mechanism connected with said stock and provided with a feed-ratchet arranged with its axis coincident with the axis of the stock and in position to have its teeth engaged by said pawl.
